UNITED STATES PATENT OFFICE.

EARL J. ASKREN, JOHN F. WORMAN, AND CHARLES F. ZWICK, OF INDIANAPOLIS,
INDIANA.

SHIELD FOR MOTOR RADIATORS.

1,421,120.

Specification of Letters Patent. Patented June 27, 1922.

Application filed March 6, 1920. Serial No. 363,753.

To all whom it may concern:

Be it known that we, EARL J. ASKREN, JOHN F. WORMAN, and CHARLES F. ZWICK, citizens of the United States, and residents 5 of Indianapolis, county of Marion and State of Indiana, have invented a certain new and useful Shield for Motor Radiators; and we do hereby declare that the following is a full, clear, and exact description thereof, 10 reference being had to the accompanying drawings, in which like numerals refer to like parts.

The chief object of this invention is to provide improved damper means for regulating the amount of air passing through a 15 motor radiator. This invention in particular is an improvement upon the device shown in Patent No. 1,277,589.

Another feature of the invention consists 20 of simplifying and strengthening the parts comprising the invention, whereby the cost of manufacturing the same will be greatly reduced.

A further feature of the invention consists 25 in constructing the parts thereof in such a manner that the invention may be readily attached to a radiator of a water cooled internal combustion engine found upon motor cars and the like, said attaching means 30 securing said shell to the radiator in an improved manner.

A further feature of the invention consists in constructing the same so that the invention may be adjustably secured to all cars 35 provided with flat front radiators.

The full nature of this invention will be understood from the accompanying drawings and the following description and claim.

40 In the drawings Fig. 1 is an elevational front view of a motor vehicle radiator to which the invention has been attached. Fig. 2 is a vertical sectional view of the same taken on the line 2-2 of Fig. 1. Fig. 3 is 45 a rear view of the radiator shield. Fig. 4 is a view illustrating the general method of attaching the radiator shield to any square front radiator. Fig. 5 is an enlarged sectional view showing in detail the method of 50 securing the shield to the radiator. Fig. 6 is an end view of the securing means shown in Fig. 5. Fig. 7 illustrates the means positioned upon the dash board of the motor vehicle by which the damper construction of 55 the shield may be controlled.

In the drawings 10 indicates the customary radiator provided with the usual fins 11 and water tubes 12. A shield plate 13 is adapted to be positioned forwardly of said radiator and to be secured thereto in an improved manner, particularly illustrated in Figs. 4, 5 and 6. Herein the shield plate 13 is shown formed with socket depressions 14, the same seating suitable bolt means 15 which are adapted to extend through said 60 radiator adjacent the tubes thereof and between the fins, as shown. Upon the other end of said bolt is positioned a reenforcing plate 16, said plate being provided with inwardly turned flanged edges 17, the same 65 adapted to be positioned adjacent the usual horizontal fins 11. In this manner the plate 16 substantially abuts several of the fin edges, as shown particularly in Fig. 5, which 70 provides an improved and substantial bearing or supporting base. The reenforcing plate 16 is also provided with a plurality of outwardly projecting flanges 18, the same 75 being in spaced relation with each other so as to engage and grip the retaining nut 19 80 and hold the same non-rotatably in position upon the rod 15, as shown. From the foregoing it will be understood that the plate 13 may be rigidly secured to any radiator 85 without danger of becoming loose or bending the fins of the radiator.

The damper arrangement provided by said shield 13 is formed of but few parts and those of simple construction, to wit, the shield plate 13 is provided with a plurality 90 of longitudinally extending slots 20. Said slots are in parallel and spaced relation with each other, and in the connecting portions between the same there is formed suitable reinforcing and ornamental ribbing 21. Between the radiator and the shield, and secured to the rear of the latter is a damper plate 22, the same being provided with a plurality of similar slots 23 formed in said plate. The slots 23, however, are shown separated by the longitudinal spacing portions 24, and said spacing portions are herein shown connected by suitable connecting portions 25 formed integral therewith and the plate 22. In the drawings said connecting 100 portions 25 are positioned substantially midway between the top and bottom of the damper plate and are substantially in alignment with each other. As shown in Figs. 1 and 2 the slots 23 and the longitudinal 105 110

spacing portion 24 of the damper plate 22 are adapted to register with the longitudinal slots 20 of the shield 13 to respectively position the damper in the open position or 5 in the closed position.

The damper plate 22 is herein shown provided with a plurality of transversely extending guide slots 26, the same receiving and seating suitable guide pins 27 supported 10 upon the shield plate 13. Integral with the plate 22 is a transversely extending portion 28, the same being in alignment with the transverse connecting portions 25. Suitable means are provided for reciprocating 15 the damper plate 22 upon the guide pins 27 from the extreme closed position illustrated in Fig. 1 to the extreme open position, or to any intermediate position desired, said reciprocating means, as shown clearly in 20 Figs. 1, 2, 3 and 7, comprising a lever handle 29 pivotally mounted in the dash board of the motor vehicle and having a shaft portion 31 extending therethrough, as illustrated. Suitably secured upon the dash and 25 adjacent the lever 29, and cooperating therewith, are a pair of stop pins 32 which indicate the extreme open and closed positions of said damper construction and limit the movement of said lever handle. Positioned 30 above said stop pins and substantially concentric with the pivotal support of the lever 29 is an arcuate rack 33 provided with a plurality of substantially radial notches 34 in which the free and coiled end 35 of the 35 lever 29 is adapted to be seated. As shown in Fig. 7, a suitable plate 36 is provided with the pivot support 37, and the arcuate rack 33 and is secured to the dash 30 by means of stop pins 32. It will also be noted 40 from Fig. 2 that the handle 29, the latching portion 35 and the shaft portion 31 are composed of a single rod member, and as formed the portions 29 and 35 form a spring handle which is so bent as to force the free 45 end 35 into frictional engagement with the

arcuate rack and seats the end in one of the notches 34. A rock shaft 38 is suitably connected to the pivot shaft 31 by means of the connecting plate 39, as shown.

Positioned upon the front of the shield 50 plate 13 and suitably secured thereby by means of rivets or bolts 40, is a triangular cap portion 41, said cap covering a triangular opening 42 so as to provide a recess. Upon the opposite side of the shield plate 55 a cross member 43 is suitably secured by means of the bolts or rivets 40, as shown. The cross member 43 provides a bearing at the apex of the triangular opening for the rock shaft 38, as shown, and the same extends through said bearing and upon its end there is secured a link 44, the same being connected at its opposite end with the transverse actuating portion 28. From the foregoing it will be understood that when the 60 lever 29 is turned, the rock shaft 38 transmits the motion thereof to the actuating portion 28 which reciprocates the plate 22 to open, close or adjust the position of said longitudinal openings to regulate the 65 amount of air passing through the radiator.

The invention claimed is:

In a radiator shield construction a shield plate provided with a plurality of parallel longitudinal openings, a damper plate 75 provided with similar openings, the latter openings being registrable with the former openings, said shield plate having a recess in one edge thereof, a bar secured to the other side of said shield plate adjacent the recess, 80 a rocking link pivotally supported in said recess upon said bar, a rock shaft for rocking said link, and means for rocking said shaft.

In witness whereof, we have hereunto affixed our signatures.

EARL J. ASKREN.
JOHN F. WORMAN.
CHARLES F. ZWICK.
